UNITED STATES PATENT OFFICE

1,940,687

ELECTROMAGNET

Ernest McAfee, Kansas City, Mo., assignor of one-half to George W. Meyer, Kansas City, Mo.

Application October 5, 1931. Serial No. 566,979

1 Claim. (Cl. 175—367)

This invention relates to improvements in electromagnets and particularly to an electromagnet operable by alternating current.

The principal object of this invention is the provision of an electromagnet having a laminated magnetic pole piece in which is embedded a coil in parallel relation with the laminations of said pole piece.

Another object of the present invention is the provision of an electromagnet constructed in such a manner as to be effectually magnetized when alternating current is being passed through the coil or coils contained therein.

Other objects of this invention are the provision of an electromagnet that is simple in construction, effective in operation and inexpensive to install, due to the elimination of the usual rectifier which is now being used with the commercial electromagnet when alternating current is used.

Reference will now be had to the drawing, in which:

Figure 1 is a plane view of an electromagnet embodying this invention.

Fig. 2 is a sectional view taken on line II—II of Fig. 1, and

Fig. 3 is a plane view of a modified form of the electromagnet constructed for use with a polyphase current.

In the drawing, like reference characters designate similar parts throughout the several views, and the numeral 10 indicates a pole piece made up of a series of parallel, insulated laminations 12 of a suitable magnetic material, such as iron, and having a closed coil-receiving groove 14 formed therein for the reception of a coil of insulated conductor wire 16. The coil of wire is so positioned in the pole piece 10 that the strands of wire making up the coil are in substantially parallel relation with the laminations of the pole piece. The groove 14 does not extend through all of the laminations of the series, thereby presenting a laminated connection between the inner portion 18 of the case and the outer portion 20 thereof.

Since the laminations 12 are preferably made up of rather thin material, it is deemed advisable to provide relatively thick laminations on the outer surfaces to serve as a protective covering.

Bolts 22 are passed through holes formed through the laminations and serve to hold the same in fixed relative position. The bolts are provided with countersunk heads and are positioned at the pole surface to present a smooth contacting surface for the armature or material to be attracted.

When used for certain purposes, it is obvious that the entire magnet or parts thereof might be covered with an electric insulating material for the purpose of protecting the parts and to preclude to a large extent, possible fire hazards. The

ends of the coil through the intermediary of conductors 24 and 25 are connected to any suitable supply of alternating current through line wires 26 and 28. The polarity of the pole portions 18 and 20 is determined by the direction of the flow of the current in coil 16, also the strength of the magnetic flux depends to a large extent on the ampere turns of the coil. When it is desired to use this electromagnet with a polyphase current, it is necessary that the windings be changed to meet the varying conditions. The magnet shown in Fig. 3 is suitable for use with a three-phase current. The pole piece 30 is provided with two closed grooves 32 and 34 which are positioned in uniformly spaced relation and are adapted to receive coils 36 and 38 respectively. As indicated by the drawing, these coils are connected in the usual manner to the three-phase circuit wires 40 which are connected to any suitable source of power.

This type of alternating current electromagnet when properly proportioned will produce substantially uniform magnetic flux through the entire pole surfaces as long as the coil is being supplied with alternating current of proper phase.

Furthermore, this magnet will not become excessively heated. However, care must be taken in winding the coil to compensate for the inductive kick when the coil is opened. It is apparent that this electromagnet is adapted for commercial use where only an alternating current is available without the use of a motor generator or any type of rectifier which is now necessarily used. The principal features of this type of electromagnet are well suited for use in many electrical appliances such as motors, etc.

While the preferred forms of this invention have been shown and described, it is apparent that many modifications might be made without departing from the scope of the appended claim.

Having thus described the invention, what is claimed as new and desired to be secured by Letters Patent is:

An electromagnet comprising a laminated pole piece having parallel grooves formed in one face thereof; coils mounted in said grooves in parallel relation with the laminations of said pole piece, whereby when an alternating electric current is passed through said coils, said pole pieces will be magnetized.
